(57) **CLAIM**

The ornamental design for a nail clipper clippings catcher, as shown and described.

DESCRIPTION

FIG. 1 is a perspective view of the nail clipper clippings catcher showing my new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear top view thereof.

The broken line illustration of unclaimed portions of the nail clipper clippings catcher forms no part of the claimed design.
